UNITED STATES PATENT OFFICE.

JOSEPH D. STAUFFER, OF SUPLEE, PENNSYLVANIA.

RAILROAD CONCRETE TIE

1,148,414.

Specification of Letters Patent. Patented July 27, 1915.

Application filed January 15, 1915. Serial No. 2,412.

To all whom it may concern:

Be it known that I, JOSEPH D. STAUFFER, a citizen of the United States, residing at Suplee, in the county of Chester and State 5 of Pennsylvania, have invented certain new and useful Improvements in Railroad Concrete Ties; and I do hereby declare the following to be a full, clear, and exact description of the invention, such as will enable 10 others skilled in the art to which it appertains to make and use the same.

This invention relates to new and useful improvements in railroad ties and has for its object the provision of a device of the 15 above character which is adapted to provide a simple, safe and reliable support for the rails of railroads.

Another object of my invention is the provision of a device which will eliminate 20 the use of wood for such purposes and substitute therefor a material which is substantially indestructible.

A further object of my invention is the provision of a device of the above character 25 which will effectively prevent the rails of railroads from spreading and causing wrecks thereby.

A still further object of my invention is the provision of a novel means for attaching 30 the rails in position on the tie and providing a means whereby the attachment may be adjusted according to the wear thereon.

With the above and other objects in view I will now proceed to describe my invention 35 in the following specification and accompanying drawings, in which,

Figure 1 is a detail perspective view of my improved railroad tie showing the rails as they would appear in position thereon, 40 Fig. 2 is a top plan view of my improved tie showing the rails in position, Fig. 3 is a longitudinal sectional view of my improved tie taken on line 3—3 of Fig. 2, Fig. 4 is a transverse sectional view of my improved 45 tie taken on line 4—4 of Fig. 1, and Fig. 5 is a detail view of the rail attaching means.

Referring to the drawings by characters of reference 1 indicates the body portion of my improved tie which is preferably 50 formed of plastic material, such as concrete or the like. A suitable centrally located longitudinally extending reinforcing plate 2 is embedded in the concrete and has welded thereon the laterally extending reinforcing plates 3. These plates 3 are prefer-

ably of thinner material than the centrally located plate 2 and are adapted to extend throughout substantially the entire length of their respective sections of the tie. Suitable reinforcing plates 4 are also embedded in the concrete at points near the upper and lower surfaces as clearly shown in Fig. 1. The uppermost plate 4 is adapted to act as a rest for the base of the rail when the same is in place. Suitable bolts 5 are extended through apertures in each of the plates, as clearly shown in the figures, and are provided with nuts by means of which the whole is clamped firmly together.

On the upper surface of the tie, as will be apparent in Fig. 1, a portion of the concrete is cut away to form the rest in which the rail is adapted to seat, the bottom of this rest being formed by the uppermost plate 4 which serves both purposes of a rest and a reinforcing plate. Immediately adjacent the rest and at suitable points with relation to the edges of the tie I also provide the apertures 6 through which the shank 7 of a suitable bolt is adapted to pass. This bolt 80 is provided with the usual head 8 which is adapted to be embedded in the concrete and is of sufficient area to prevent the same from becoming loosened or displaced therein. The shank 7 of the bolt is provided at its upper end or the end opposite the head with a suitable transverse aperture 9, through which a key indicated by the numeral 10 is adapted to extend. From the drawings it will be apparent that the wedge key illustrated in Fig. 5 may be eliminated and a suitable split key may be substituted therefor which owing to its bifurcated end may be securely fastened in place in the aperture in the bolt 7. A suitable rail engaging plate 95 11 is provided and is formed with a central aperture through which the bolt 7 extends. This plate is arranged to engage the flange of the rail with which it cooperates and firmly locks the same in the rail seat. After 100 the rails have been seated in the proper position the only operation remaining to be performed is that of placing the plates 11 in position and allowing the elongated ends thereof to lie over the flanges of the rails. 105 Upon placing the keys in position it will be apparent that the plates 11 will be prevented from becoming displaced and should any wear take place therein upon further driving the keys into the apertures 9, it will be 110

22
apparent that the plates may be brought firmly against the flanges of the rails and any wear may be thus taken up.

While in the foregoing I have shown and 5 described the preferred embodiment of my invention I wish it to be understood that I may change the specific arrangement and combination of parts without in any way departing from the spirit and scope of my 10 invention as defined in the appended claims.

What is claimed is:—

1. In a composition railroad tie, a body portion of plastic material, a centrally located reinforcing plate extending throughout 15 the entire length of said body portion, auxiliary reinforcing plates secured to the central reinforcing plate, the topmost auxiliary plate being adapted to form a seat for the rail when the same is in place, and 20 means connected to the tie to hold the rail in position.
2. In a composition railroad tie, a body portion comprising two sections formed of plastic material, a centrally disposed longitudinally extending reinforcing plate embedded in said plastic material, the middle 25 portion of said plate being thicker than the end portions thereof, auxiliary reinforcing

plates connected to the centrally located reinforcing plate and embedded in the plastic material, the uppermost auxiliary reinforcing plate being adapted to form a seat for a railroad rail when the same is in place, and means immediately adjacent the rail seat to rigidly secure the rail therein when the 25 device is in use.

3. In a device of the character described a body portion comprising two sections formed of plastic material, a longitudinally extending centrally disposed reinforcing plate embedded in said plastic material, auxiliary reinforcing plates connected to the centrally disposed reinforcing plate, bolts embedded in said sections, each of said bolts having transversely extending apertures therein, and plates adapted to slip over said bolts and be secured thereon and thereby hold the rail in position when the device is in use.

In testimony whereof I affix my signature in presence of two witnesses.

JOSEPH D. STAUFFER.
